UNITED STATES PATENT OFFICE

VALENTINE J. MOHLER, OF RIVER FOREST, ILLINOIS, ASSIGNOR TO ADDRESSOGRAPH COMPANY, OF WILMINGTON, DELAWARE, A CORPORATION OF DELAWARE

PRINTING DEVICE FRAME BLANK

Application filed December 4, 1929. Serial No. 411,416.

This invention relates to frames for printing devices of that class which are adapted to be stored in accordance with a card index system and to be run through addressing or 5 other machines for printing. These devices commonly comprise a frame and one or more plates having printing characters embossed thereon the frame being provided with retaining means for detachably securing the 10 plate or plates in place thereon. To accommodate the requirements of trade the printing devices have been made up in many types requiring the provision of special dies for stamping the frames and the number of 15 types is constantly increasing with the extension of uses of the printing devices. Each type of printing device has heretofore been made as a separate unit and this has required the provision of a great many dies some of 20 which are duplicates. The sales of the different types are more or less irregular in volume and the result is that large quantities of the different types of frames are constantly carried in stock. Where dies are 25 used interchangeably for different types delays occur sometimes in filling a large order for a certain type because of the use of the dies in making some other type or types. Where certain dies are used in producing a 30 number of different types there is always the tendency to confusion and delay and the only other recourse is the provision of a complete set of dies for each type which would include many duplicates.

35 The generic object of the invention is to provide a standard frame blank which is partly made in the form of a frame and which can be completed in any type desired.

It is also the object to enable the standard 40 frame blank to be made in quantities on a production basis and kept on hand to be quickly finished in any type required to fill orders received or to maintain stock requirements according to any system that may be 45 prescribed.

I have illustrated the invention in the accompanying drawing in a form suitable for the purpose and referring thereto,

50 Fig. 1 is a front view showing the standard frame blank.

Fig. 2 is a back view thereof.

Fig. 3 shows a blank from which the standard frame blank of Figs. 1 and 2 is made.

Fig. 4 is an enlarged sectional view on 55 the line 4—4 of Fig. 1.

Fig. 5 is a similar view on the line 5—5 of Fig. 1.

Fig. 6 is a similar view on the line 6—6 60 of Fig. 1.

The frames are stamped from sheet metal and a strip 7 is produced in a preliminary operation and is then provided with beads 8, 8 on its front, spacing flanges 9, 9 on its back, and end stops 10, on its front, leaving 65 openings 11, in subsequent operations to form the standard frame blank 12. The spacing flanges 9 space the printing devices apart in a drawer or in a stack and thereby protect the faces of the printing characters 70 that are subsequently mounted on the frame. Each flange is formed by bending the marginal end portion of the sheet 7 to provide an inner flat section 13, Figs. 4 and 5, substantially parallel with the body of the blank 75 but offset therefrom and connected therewith by a shoulder 14, an outer flat section 15 also substantially parallel with the body of the blank and connected by a rib 16 with the flat section 13, and a facing section 17 80 overlapping the flat sections 13 and 15 and the rib 16, and lying in the plane of the face of the body of the blank and with its edge abutting the shoulder 14. The ribs of the 85 spacing flanges of one printing device will engage the facing sections of another printing device to space the devices apart, as above set forth. The facing sections form smooth surfaces for handling the printing devices and for the ribs of another printing 90 device to slide on. The end stops 10 are joined to the main body of the blank along the shoulder 14, Fig. 5. The beads and end stops constitute some of the retaining devices for holding a card and one or more 95 printing plates on the frame. Additional retaining devices are produced on the standard blank as may be required for different types of frames to hold cards and plates of different sizes, shapes and numbers. In or-

der to provide a standard frame blank finished as completely as possible for the many varieties of frames it is necessary to have the retaining devices on the blank made and disposed in a manner to function properly in any type of frame. It has been customary to use beads at the top and bottom of the frame as shown in the drawing but the retaining devices at the ends of the frame have been made of different kinds and in different sizes and shapes designed for each particular frame, and this has involved, as before stated, the provision of as many different dies as there are different retaining devices. I avoid this by providing three end stops of substantially equal length spaced apart and from the top and bottom of the blank and arranged in vertical alignment adjacent each end of the frame. I have found that if these end stops aggregate in length substantially one-half the height of the frame from top to bottom they will serve for any of the types of printing devices which have been used and for any others.

My invention enables the standard blank Figs. 1, 2 to be made as a stock production job in a continuous run with one set-up of dies on a machine which may continue from day to day according to trade requirements. This also enables the work to be done by operators proficient in the production of the particular product and promotes efficiency and uniformity of product. It enables the factory to keep on hand a supply of standard blanks, which are partly made frames, and which can be turned over to other operators to finish quickly into different types of frames to supply particular orders. This also promotes efficiency and uniformity of product and enables orders to be filled with greater speed than has been customary where frames to fill orders have been made in continuous operations direct from the sheet. It is only necessary to maintain a stock of the standard blanks on hand and to keep supplying these standard blanks as fast as they are required for use in making up different types of frames to supply orders and since the finishing operation can be performed quickly it is believed that it will not be necessary to keep on hand any more than a small stock of each type to fill small orders. The invention simplifies the die operations and systematizes the work so that production may be increased and costs reduced.

I have shown the invention in a form which I find satisfactory to accomplish the objects of the invention but changes in the details of construction may be made to satisfy different requirements and I reserve the right to make any changes within the scope of the following claims.

I claim:

1. A standard blank for printing device

frames having at each end a plurality of retaining devices of substantially equal length spaced apart in equal amounts from each other and from the top and bottom of the blank and arranged in alignment, the retaining devices at one end being disposed opposite the retaining devices at the other end of the blank.

2. A standard blank for printing device frames having at each end a plurality of retaining devices spaced apart in alignment, the aggregate length of said devices at each end of the blank being substantially equal to one-half the height of the blank from top to bottom thereof, the retaining devices at one end being disposed opposite the retaining devices at the other end of the blank.

3. A standard blank for printing device frames having at each end a plurality of retaining devices spaced apart from each other and from the top and bottom of the blank, the retaining devices at each end of the blank arranged in alignment, the aggregate length of said devices at each end of the blank being substantially equal to one-half the height of the blank from top to bottom thereof, the retaining devices at one end being disposed opposite the retaining devices at the other end of the blank.

4. A standard blank for printing device frames having at each end a plurality of retaining devices, the retaining devices at one end being located opposite the retaining devices at the other end of the blank and all of said retaining devices being of substantially equal length, the retaining devices at each end of the blank being spaced apart substantially equally from each other and from the top and bottom of the blank and arranged in alignment, the aggregate length of said retaining devices at each end of the blank being substantially equal to one-half the height of the blank from top to bottom thereof.

5. A printing device frame blank comprising a body having its end portion bent to provide a spacing flange on the back of the blank, there being a shoulder on the front of the blank connecting the spacing flange with the body, the marginal edge of said end portion being bent inwardly from the outer edge of the spacing flange to form a facing section on the front of the blank disposed in the place of the face of the body with the free edge thereof abutting said shoulder.

6. A printing device frame blank comprising a body having a spacing flange along a marginal edge thereof and including an inner flat section substantially parallel with the body and offset therefrom, a shoulder connecting the inner flat section and the body of the blank, an outer flat section substantially parallel with the body, a rib connecting the inner and outer flat sections, and a facing section lying in the plane of the face of the

body and overlapping the flat sections and the rib and abutting said shoulder.

7. A printing device frame blank comprising a body having a formed marginal edge 5 providing a shoulder and including a facing section inwardly directed and disposed in the plane of the face of the body with the free edge thereof abutting said shoulder, and end stops protruding above said plane and struck 10 from said body at said shoulder and extending upwardly in alignment therewith.

8. A printing device frame blank comprising a body having a spacing flange along a marginal edge thereof and including an inner 15 flat section substantially parallel with the body and offset therefrom, a shoulder connecting the inner flat section and the body of the blank, an outer flat section substantially parallel with the body, a rib connecting the inner and outer flat sections, a facing section inwardly directed and lying in the plane of the face of the body and overlapping the flat sections and the rib and abutting said shoulder, and end stops protruding above said 20 plane and struck from said body along said shoulder.

9. A printing device frame blank comprising a body having a spacing flange along a marginal edge thereof and including an inner 30 flat section substantially parallel with the body and offset therefrom, a shoulder connecting the inner flat section and the body, an outer flat section substantially parallel with the body, a rib connecting the inner and outer 35 flat sections, and a facing section inwardly directed and lying in the plane of the face of the body and overlapping the flat sections and the rib with the free edge thereof abutting said shoulder.
